C. BOOZE.
WALL PAPER.

No. 20,219.

Patented Oct. 21, 1890.

UNITED STATES PATENT OFFICE.

CHARLES BOOZE, OF BUFFALO, NEW YORK, ASSIGNOR TO M. H. BIRGE
& SONS, OF SAME PLACE.

DESIGN FOR WALL-PAPER.

SPECIFICATION forming part of Design No. 20,219, dated October 21, 1890.

Application filed September 27, 1890. Serial No. 366,372. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

10 The leading feature of my design consists of continuous branches of leaves and flowers of the rose intertwined and arranged in a wavy horizontal line below an ornamental stencil border composed of serpentine or wavy 15 intersecting lines, forming a series of connected circles, with rosette ornaments arranged in the circles and light parallel lines arranged horizontally above and below the connected circles. A spray or light branch 20 of the flowers and leaves extends upwardly

from the main branches and runs under and above the ornamental border. Below the horizontal wavy line of flowers and leaves is arranged a horizontal border composed of light parallel lines and a stencil ornament 25 consisting of connected leaves and flowers and a light horizontal line below said ornament, as represented in the accompanying photograph.

My design is more particularly used and 30 designed for a ceiling decoration or border.

What I claim is—

The design for wall-paper herein shown and described.

Witness my hand this 13th day of September, 1890.

CHARLES BOOZE.
